UNITED STATES PATENT OFFICE

WILLIAM WALDRON, OF CHICAGO, ILLINOIS, ASSIGNOR OF ONE-HALF TO W. S. CLARK,
OF CHICAGO, ILLINOIS

SELF-CLOSING, DOUBLE-ACTING DOOR

Application filed August 3, 1928. Serial No. 297,298.

This invention relates to a self-closing double-acting door, and refers more particularly to a door especially adapted for uses wherein it is necessary to provide a door 5 which will swing in either direction from a closed or normal position with equal facility, close automatically and yet involve only a minimum of mechanical parts.

Such a door is of particular utility in industrial refrigerator installations, particularly in the large packing houses, meat markets and the like. The door will be described with particular reference to use with refrigerators, but it is to be understood at the outset that I do not wish to limit myself in any way to a door which can only be used with refrigerators, since the concept of the present invention comprises a self-closing double-acting door adaptable for use in any industry 20 and at any place where it may be found to be of advantage or utility.

Among the salient objects of the present invention are to provide a door so designed that, when it is swung to an open position, it will 25 automatically swing back to normal or closed position when the force which swung it open is removed; to provide a door of the character described designed to be swung in either direction from a normal or closed position 30 with equal facility; to provide a self-closing double-acting door making use of no springs or weights but operating on a swinging jamb provided with an eccentric head; to provide means for facilitating the movement 35 of said jamb comprising a ball bearing on which said jamb rotates; to provide in a door of the character described means for automatically and positively locking the door in normal or closed position when it is automatically returned after having been swung 40 to an open position; to provide means associated with such a door adapted to prevent fanning of the door in closing after having been swung to an open position; to provide 45 a door of the character described which is positively locked in closed or normal position and which can only be opened by force applied against the bumper carried by the door; to provide in a door of the character described 50 means for positively locking the door in

closed position adapted to function regardless of the direction in which the door is swung; to provide a door equipped with bumpers on both sides thereof; to provide in combination with a door a rotary jamb of the character described and a non-swinging jamb associated with the framework surrounding the door adapted to rotate or otherwise give to absorb the shock of the door in closing; to provide in a construction of the character described means for lubricating the ball bearing on which the revolving jamb rotates; to provide in the stationary upper frame of the support surrounding the door recesses on both sides of said upper frame forming shoulders adapted to receive the locking means carried by the door; to provide in a construction of the character described means for positively preventing the swinging of the door to open position, short of distortion of the locking means, unless the force to open the door is applied to the bumper; to provide means for preventing fanning and for simultaneously locking the door in fixed or closed position, comprising a vertically movable rod carrying a roller on its upper end and associated through link mechanism with the bumper, said rod and roller being maintained under the tension of a spring; to provide a construction in which force applied to the bumper releases the spring tensioned roller from engagement with the recesses on the upper frame, permitting the roller to ride over the track in said upper frame and thus permit the door to be swung open; to provide in a construction of the character described double acting locking means, i. e., one on each side of said door independently functioning to fixedly and simultaneously lock the door in closed position; to provide slanting cam-like surfaces projecting from each side of the upper frame of the supporting structure for the door functioning to receive the roller forming part of the locking mechanism when the door is closing to compress the spring and permit the roller to ride across the track on the upper frame until it drops into said recess and shoulder, at which time the spring expands to normal position to force the roller to drop into the recess; to provide a flexible

lining or stripping, for instance, of rubber, adapted to make the various connections tight when the door is closed; and in general to provide improvements of the character referred to.

The door of the present invention is particularly adapted for use in refrigerators, and more particularly in industrial refrigerators where small trucks are used as the motive power for conveying material into and out of the refrigerator and where it is essential that the door be positively locked in closed position and yet be capable of being easily opened by the force of the truck being applied against the bumper of the door.

Many other objects as well as advantages will be more apparent from the following description.

Fig. 1 is a fragmentary elevational view of the door of the present invention installed in a suitable supporting structure.

Fig. 2 is a transverse sectional view taken on line 2—2 of Fig. 1 looking in the direction of the arrows.

Fig. 3 is an enlarged fragmentary vertical sectional view illustrating the revolving jamb provided with an eccentric head and operating on a ball bearing.

Fig. 4 is a transverse sectional view taken on line 4—4 of Fig. 3 looking in the direction of the arrows.

Fig. 5 is a fragmentary elevational view illustrating a portion of the door supporting structure and the door itself in open position.

Fig. 6 is a vertical sectional view taken on line 6—6 of Fig. 1 looking in the direction of the arrows.

Fig. 7 is a cross sectional view taken on line 7—7 of Fig. 6 looking in the direction of the arrows.

Fig. 8 is a cross sectional view taken on line 8—8 of Fig. 6 looking in the direction of the arrows.

Referring more in detail to the drawings, the supporting structure comprises two sides, 1 and 2, a base 3 and an upper frame 4. The sides 1 and 2 as well as the top frame 4 may be constructed of metal, wood or other material suitable for the purposes for which the door is to be used. The base 3 may comprise a floor if desired which may be of wood, hydraulic cement, concrete or the like. Mounted on the base 3 and spaced on opposite sides immediately adjacent the walls 1 and 2 are supporting plates 5 and 5' attached to the base 3 in any suitable manner, for instance, through the medium of the screws 6. Where the base 3 comprises hydraulic cement or concrete the supporting plates 5 and 5' may be embedded therein. The plate 5' supports a jamb 7, which in the present instance takes the form of a tubular structure of metal or other suitable material so mounted as to be freely rotatable relative to the base 5'. The particular mechanism for permitting

free rotation of the jamb 7 in either direction is not illustrated in the drawings, since this mechanism may be any conventional design and is well known to those versed in mechanics. The purpose of providing this freely rotatable jamb 7 will be hereinafter brought out.

The plate 5 may be provided with the upwardly projecting tubular projection 8 (Fig. 3) in which is mounted a disc 9 dished on its upper surface to accommodate a ball 10 adapted to function as a bearing for the swinging jamb designated as a whole at 11. This jamb 11 may comprise an elongated open ended tube 12, the lower end of which is closed by means of a plug 13, the lower surface of which plug is dished to accommodate the ball bearing 10 previously described, the arrangement being such that the closure plug 13 which moves with the jamb 11 when the latter is swung is supported on the ball bearing 10. The upper surface of the plug 13 may be dished, as shown at 14, for the purpose of receiving lubricant which may be fed through the duct 15 into the space 16 surrounding the lower end of the plug between it and the disc 9. The plug 13 is suitably keyed or otherwise connected with the tube 12 so that the plug and tube move as a unit. Lubricant may be supplied to the reservoir 14 through the aperture 17 in the wall of the tube 12. It is to be noted that there is a slight clearance at 18 between the closure plug 13 and projection 8 so that there will be no friction at this point when the jamb 11 is moved.

The jamb 11 is suitably fixedly connected to one edge of a door designated as a whole at 19, which in the present instance may comprise a central ply 20 of cork surfaced on both sides with a layer 21 of wood over which is applied a surfacing of metal 22. It is to be understood that while I have illustrated a door in which certain materials are used in its construction for refrigerator purposes, that I do not, as heretofore pointed out, limit the invention to use with any particular kind of door. The upper and lower edges of the door 19 may be provided with the flexible strips 23 which may be made of rubber or other suitable flexible material for the purpose of making a tight joint similar to weather stripping, when the door is in closed or normal position. This flexible stripping material 23 may be mounted in the upper and lower edges of the door in the manner illustrated in Fig. 6 through the instrumentality of the block 24. Similarly, one side edge of the door, namely, that side which is disposed adjacent the jamb 7 is also provided with stripping 23. In a similar manner, stripping 23 is mounted in the edges of each of the edges 1 and 2 of the supporting frame structure.

Screws or other suitable fastening elements 130

25 may pass through the door registering with the blocks 24 to lock said blocks in position. The door 19 may be provided with a window 26 through which a view may be had of the space on the opposite side of the door for the purpose of avoiding collision.

The jamb 11 is mounted so as to operate on an eccentric as will now be described. The upper end of the tubular column 12 will be 10 closed by means of a cap 27, which latter is provided on its upper face with an eccentrically mounted head 28. This head 28 is adapted to be confined by the housing 29 of a ball race 30. At this stage of the description 15 it may be well to point out that the face of the channel in which the ball race moves is preferably curved, as shown at 30', to the radius or arc of a circle to permit said ball race to freely move and not bind when the 20 door is swung on the eccentric 28. The housing 29 is mounted in a supporting structure 31 embedded in a suitable inwardly cut recess in the upper frame 4 and connected thereto by means of the screws or other suitable fastening elements 32.

The arrangement is such that the door 19 may be swung in either direction from its closed or normal position, the eccentric 28 acting as the upper pivot and the ball bearing 10 functioning as the lower pivot. In such swinging movement, therefore, the jamb 11 as well as the door will be caused to tip forwardly from the wall of the supporting structure, as clearly illustrated in Fig. 5. Through 35 this arrangement, the weight which normally would be balanced by having the pivots in the same vertical plane is thrown off balance, which is the force utilized in the present invention for causing the door to automatically 40 close when the force which swung it open is removed.

Describing now another feature of the present invention comprising the double acting means for preventing fanning of the door and simultaneously functioning to fixedly lock the door in closed position, the under face of the upper frame 4 may be cut away to provide a right angle recess (Fig. 6) adapted to accommodate the recessed or shoulder portion 33 of a metal plate made up of the portion 33, flat track 34, sloping face 35 and flange 36 adapted to be connected to a frame 4 in any suitable manner, such, for instance, as by the medium of screws or other fastening elements 37. In one embodiment of the invention, two of these plates are disposed immediately adjacent each other in abutting relationship, the cut away portion 33 of one plate being disposed on the opposite side of the frame 4 from the cut away portion 33 of the adjacent plate, as illustrated clearly in Fig. 1, for a purpose to be now described.

On each side of the door 19 there is disposed a bumper 38 pivotally mounted 65 through the medium of the pin 39 to a bracket

40 (Fig. 6) carried by the door. The bumper takes the form of a semicircular piece of metal so mounted on the bracket 40 as to leave a space 41 between its free end and the face of the door. Thus, when a truck, hand or other 70 instrumentality, applies force to the outer face of the bumper, it will swing on pivot 39 to decrease the space 41 between the free end of the bumper and the surface of the door. Normally, as illustrated in Fig. 8, the inner 75 face of the bumper is in contact with a roller 42. Force applied against the outer surface of the bumper 38 is, therefore, communicated through the contacting of the inner surface of said bumper with said roller 42. The 80 roller 42 is carried by a bifurcated link 43, which latter carries on its other end a roller 44 adapted to contact the face of the door. The roller 42 is also connected to a bifurcated link 45 mounted for pivotal movement in a bracket 46 through the medium of a pin 47. The link 43 is provided with an extension 48 on which is fixedly carried a pin 49 with which the lower end of an upright rod 50 is 85 adapted to be connected. The arrangement is 90 such that force applied against the outer surface of the bumper 38 causes the roller 42 to roll on the inner surface of the bumper 38, which in turn transmits pivotal movement to the links 43 and 45 whereby the roller 44 rolls 95 downwardly on the surface of the door 19. This downward movement of the link 43 carries with it the upright rod 50 for a purpose now to be described.

The rod 50 terminates in a bifurcated connecting bracket 51 adapted to receive the lower end 52 of a shorter rod 53, the connection between the elements 51 and 52 taking the form, for instance, of the pin 54. The upper end of the rod 53 is connected to a block 54 decreasing in thickness in the upper portion of its length, as shown at 55. The upper edge of the portion 55 carries a roller 56 which is adapted, when the door is in normal or closed position, to register with the recess 33 and when the door is being swung to either open or closed position to ride along the surfaces 34 and 35.

Connected to the upper surface of the door 19 is a bracket 57 having upper and lower projections 58 and 59 internally apertured to receive the rods 55 and 53, respectively. The upper projection 58 serves as a shoulder to limit the movement of the enlarged portion 54, which in turn confines the upper end of a coil spring 60 while the lower projection 115 serves to confine the lower end of said coil spring 60.

As heretofore described, there is a bumper 38 and a tripping and locking assembly actuated thereby located on each side of the door, as illustrated in Fig. 5.

The operation of the construction described will be apparent from the foregoing description. The door is hung to swing in 130

either direction. In closed or normal position it occupies the position illustrated in Figs. 1 and 6 wherein the rollers 56 on each side of the door register with their respective recesses 33 to lock the door in closed position. The door can only be opened by releasing the registration between the rollers 56 and recesses 33, which is accomplished by weight being placed against the bumper 38 releasing the roller and permitting the door to be swung open by a continuance of the force which released the roller. In open position the door occupies the position illustrated in Fig. 5. Just as soon as the force which opened the door is removed, the door of its own weight due to the eccentrically mounted jamb will return to normal position. To prevent fanning of the door, and to insure a positive locking of the door in closed position, the roller is gradually compressed against the tension of the spring 60 by rolling along the inclined surface 35 and the horizontal surface 34 until it reaches the recess 33, at which time, due to the expansion of spring 60 to normal position, will drop into the recess 33. The door is now locked in closed position and can only be opened by force applied against the bumper 38.

The door has been scientifically designed and possesses a number of points of advantage. Yet, in spite of its many advantages, there are comparatively few mechanical parts and combinations which might tend to get out of order.

35 I claim as my invention:—

1. In combination, a door mounted for swinging movement relative to a stationary frame adjacent thereto, a pivotally mounted jamb integrally associated with one side edge 40 of said door to swing therewith, a head associated with the upper end of said jamb forming a pivot eccentrically mounted relative to the lower pivot of said jamb, said lower pivot comprising a ball and socket.

45 2. In combination, a door mounted for swinging movement in either direction from a closed position relative to a stationary frame adjacent thereto, a pivotally mounted jamb integrally associated with one side edge 50 of said door to swing therewith, a head associated with the upper end of said jamb forming a substantially universal pivot eccentrically mounted relative to the lower pivot of said jamb, said lower pivot comprising a ball and socket.

55 3. In combination, a door mounted for swinging movement relative to a stationary frame adjacent thereto, a pivotally mounted jamb integrally associated with one side edge 60 of said door to swing therewith, a head associated with the upper end of said jamb forming a pivot eccentrically mounted relative to the lower pivot of said jamb, and means adapted to automatically lock the door in closed position, comprising a spring ten-

sioned latch carried by the door adapted to register with said stationary frame.

4. In combination, a door mounted for swinging movement relative to a stationary frame adjacent thereto, a pivotally mounted jamb integrally associated with one side edge 70 of said door to swing therewith, a head associated with the upper end of said jamb forming a pivot eccentrically mounted relative to the lower pivot of said jamb, means adapted to automatically lock the door when the same swings into horizontal position, comprising a spring tensioned latch carried by the door adapted to register with said stationary frame, and a movable bumper carried by the door and automatically actuatable by force applied against said bumper to release said spring tension latch from locking position to permit swinging of the door, out of horizontal position.

5. In combination, a door mounted for swinging movement relative to a stationary frame adjacent thereto, and a pivotally mounted jamb integrally associated with one side edge 80 of said door to swing therewith, said jamb being mounted to swing freely on an eccentrically disposed pivot.

6. In combination, a door mounted for swinging movement in either direction from a closed position relative to a stationary 95 frame adjacent thereto, and a pivotally mounted jamb integrally associated with one side edge of said door to swing therewith, said jamb being mounted to swing freely on an eccentrically disposed pivot.

7. In combination, a door mounted for swinging movement relative to a stationary frame adjacent thereto, a pivotally mounted jamb integrally associated with one side edge 105 of said door to swing therewith, said jamb being mounted to swing on an eccentrically disposed pivot, and means carried by the door adapted to automatically lock same in normal position, comprising a movable bumper and automatic means actuatable only by force applied against the bumper to release the door from a locked position to permit same to swing.

8. In combination, a door mounted for swinging movement relative to a stationary 115 frame adjacent thereto, a pivotally mounted jamb integrally associated with one side edge of said door to swing therewith, a head associated with the upper end of said jamb forming a pivot eccentrically mounted relative 120 to the lower pivot of said jamb, and means adapted to automatically lock the door in closed position, comprising a spring tensioned latch carried by the door adapted to register with a recess in said stationary frame.

9. In combination, a door mounted for swinging movement relative to a stationary frame adjacent thereto, a pivotally mounted jamb integrally associated with one side edge 130

of said door to swing therewith, a head associated with the upper end of said jamb forming a pivot eccentrically mounted relative to the lower pivot of said jamb, means adapted to automatically lock the door in closed position, comprising a spring tensioned latch carried by the door adapted to register with said stationary frame, and a movable bumper also carried by the door, operative connections between the movable bumper and said spring tensioned latch, said movable bumper being actuatable to automatically release said spring tensioned latch to permit the door to swing only by force applied against it.

10. In combination, a door mounted for swinging movement in either direction from a closed position relative to a stationary frame adjacent thereto, a pivotally mounted jamb associated with one side edge of said door adapted to swing with said door, a head cooperatively associated with the upper end of said jamb and mounted to provide a pivot eccentrically disposed relative 20 to the pivot associated with the lower end of said jamb, means for preventing fanning of the door and for automatically locking the door in closed position, comprising a spring tensioned means carried by the door adapted to register with a recess in that section of the stationary frame located adjacent to and above the door, an upright rod associated with said spring tensioned means and a movable bumper carried by the door actuatable only 25 by force applied against it to actuate said upright rod to automatically release said spring tensioned means from locking engagement to permit the door to be swung open.

11. In combination, a door enclosed by a frame, a jamb integrally associated with one side edge of said door and mounted for pivotal movement relative to said frame, a head cooperatively associated with the upper end of said jamb mounted to provide an eccentrically disposed pivot relative to the lower pivot for the jamb, means for automatically locking the door in closed position, comprising an upright rod having cooperatively associated with it spring tensioned means 40 carried by the door adapted to register with a recess in said frame, a movable bumper also carried by said door and having cooperative association with said upright rod, said spring tensioned means being releasable from said recess to automatically permit swinging of the door in either direction relative to said frame only by force applied against said bumper.

12. In combination, a door enclosed by a frame, a jamb integrally associated with one side edge of said door and mounted for pivotal movement relative to said frame, a head cooperatively associated with the upper end of said jamb mounted to provide an eccentrically disposed pivot relative to the lower

pivot for the jamb, means for automatically locking the door in closed position, comprising an upright rod having cooperatively associated with it spring tensioned means carried by the door adapted to register with a recess in said frame, a movable bumper also carried by said door and having cooperative association with said upright rod, said spring tensioned means being automatically releasable from said recess to permit swinging of the door in either direction relative to said frame only by force applied against said bumper, said recess communicating with a substantially horizontal track, which latter in turn communicates with an inclined track with which said spring tensioned means makes contact in the opening and closing of the door.

13. In combination, a door mounted for swinging movement relative to a stationary frame adjacent thereto, means for locking said door in closed position, comprising an upright cooperatively associated with a spring tensioned means carried by said door adapted to register with means carried by that section of the frame adjacent to and above the door for automatically causing a locking connection between the door and said frame, and automatically releasing means for releasing said spring tensioned means comprising a movable bumper actuatable only by force applied against it to actuate said upright rod and in turn release said spring tensioned means, a jamb mounted for independent rotatable movement in said frame and adapted to absorb the shock encountered in closing of the door.

In testimony whereof I affix my signature.
WILLIAM WALDRON.
